UNITED STATES PATENT OFFICE.

WILLIAM E. WHITE, OF CHICAGO, ILLINOIS, ASSIGNOR TO KALMAN STEEL COMPANY, OF CHICAGO, ILLINOIS, A CORPORATION OF DELAWARE.

TWIN CHAIR.

Application filed July 26, 1926. Serial No. 124,973.

My invention relates to road chairs and particularly to a twin chair similar to that shown in my copending application, Serial No. 124,974, filed of even date herewith.

5 An object in the construction here disclosed is to provide a chair that has the requisite area of metal for vertical reinforcement; that has no excess metal in the cross connecting elements, and that provides for a 10 rigid and permanent connection between the chair elements and the bars in a minimum of factory operations.

It will be noted that the vertical legs of the chair are in the form of loops, thus giving 15 a large area of metal for reinforcement and permitting the use of relatively small gauge wire. Further, that each wire of the legs is fully anchored to the bars; and further, that the legs are sufficiently separated 20 to permit the entrance therebetween of the largest of the coarse aggregate in the concrete. Thus voids are eliminated, and the loops insure a perfect anchorage in the concrete.

25 The invention will be more readily understood by reference to the accompanying drawing, in which;

Fig. 1 shows a length of wire after the first bending operation, a pair of elongated loops 30 being connected by a straight wire;

Fig. 2 is an edge view thereof;

Fig. 3 shows the condition after the second operation, the entire upper portion of 35 the blank being bent around a round mandril;

Fig. 4 is an edge view thereof;

Figs. 5 and 6 are edge and front views respectively showing the shape after the third operation;

40 Fig. 7 is an inverted view showing the position at the completion of the final operation;

Fig. 8 is a bottom plan view thereof;

Fig. 9 is a perspective view showing the 45 finished structure; and

Fig. 10 is a view showing a slightly modified form.

In the drawings, I have shown the steps 50 in the production of the device in order to better illustrate its practical simplicity from a manufacturing standpoint.

As a preliminary to the first operation, a section of wire of the proper gauge is cut and then bent by means of a wire working 55 machine, to the form shown in Figs. 1 and 2;

that is, a pair of parallel loops, 10, 11, joined by a straight wire, 12. In the next operation, the entire upper end of the blank is bent over to form the hooks, 13, 14, 15, 16, at the upper extremities of the wires constituting the loops, 10, 11. In this condition, the wire, 12, connects the extremities of the hooks, 14, 15. In the next operation, the loops are oscillated outwardly around mandrels indicated at X—X in Fig. 3, the loops 60 remaining in the same planes. The condition of the blank after this operation is shown in Fig. 6, the loops having been rotated 90 degrees in a common plane, thereby forming further hooks or folds of metal, 17, 18. With the blank in the form shown in Figs. 5 and 6, the reinforcing bars, indicated at A—B, are placed in the hooks, 13, 14, 15, 16, as shown, whereupon the loops, 65 constituting the legs of the chair are swung 70 upward and inward as viewed in Fig. 5, into the position of Fig. 7, in which position all the hooks are closed and the bars closely confined therein. The position of the legs 75 or loops, whether in parallelism or flared is 80 a matter of choice and is determined in the final operation.

The spacing of the chairs on the bars can be arranged as desired in order to furnish the required vertical reinforcement. The 85 operative function of the device will be obvious and further explanation is deemed unnecessary.

In Fig. 10, I have illustrated a chair of extreme simplicity, patterned after that 90 heretofore described. It comprises legs, 19, having feet, 20, of such extent as to provide adequate bearing surface. At the upper ends of the legs an eye, 21, is formed by twisting the wire around the bar, the portion 95 of the eye beneath the bar being connected to a cross member 22 that serves to laterally space the bars. The steps in the manufacture and application of the chair shown in Fig. 10, will be obvious and no illustration 100 thereof is made. The chair is very simple and may be economically made and applied.

The functional advantages of the chair shown in Figs. 1 to 9 are apparent. They include perfect anchoring of the legs in the 105 concrete; firm and rigid connection between the loops constituting the legs and the bars, thereby assuring the full benefit of the reinforcement; perfect bonding with the concrete; broad footing on the soil; adequate 110

bracing to prevent relative longitudinal shifting of the bars, and minimum weight and cost for the effect secured.

Modifications other than those here illustrated can be made by those skilled in the art, and I do not wish to be limited except as indicated in the appended claims.

I claim:

1. Means for holding a pair of parallel bars in spaced apart relation, comprising a length of wire bent to provide a connecting member the ends of which underlie said bars, the terminal portions of the wire com-

posing the connecting member being rebent and then bent around said bars and thence 15 downwardly to provide supporting legs.

2. Means for supporting and spacing a pair of reinforcing bars, comprising a length of wire bent into U shape, the legs of the U being in the form of a loop, the upper ends 20 of both loop elements being twisted more than half way around the bars, the connecting member underlying the bars at its ends.

In testimony whereof I have affixed my signature.

WILLIAM E. WHITE.
